UNITED STATES PATENT OFFICE.

GUSTAF SANDBERG, OF SAN FRANCISCO, CALIFORNIA.

CONVERTIBLE UTENSIL.

Application filed May 11, 1921. Serial No. 468,616.

To all whom it may concern:

Be it known that I, GUSTAF SANDBERG, a citizen of the United States, and a resident of the city and county of San Francisco, California, have invented a new and useful Improvement in Convertible Utensils, of which the following is a specification.

This invention relates to a convenient utensil capable of being alternately converted into a camping and folding table and a sectional carrying case.

It is one of the objects of the present invention to provide a portable, inexpensive and compact device formed of elements adjustable to serve as a carrying case in which may be transported suitable concealed objects and which device is also capable of transformation into a small table.

It is a further object of the invention to provide a convertible utensil having box-like sections hingedly connected to meet, as along a medial plane, and which sections are provided with foldable legs to be compactly arranged within the device when it is to be utilized as a carrying and packing case and which legs may be readily unfolded and locked in positions perpendicular to the plane sides of the case and which sides are adapted to serve as a table top.

Another object of the invention is to provide a complete portable set of elements constituting an unitary camp service outfit and consisting of a table-forming case, benches having elements designed to nest compactly within the case sections and also including a box for the carrying of lunches or other impedimenta and which will fit within the closed case.

The invention possesses other objects and features of advantage, some of which with the foregoing, will be made manifest in the following description of the preferred form of the invention which is illustrated in the drawings accompanying and forming part of the specification. It is to be understood that it is not intended to limit the invention to the embodiment shown by the said drawings and description, as variations may be adopted within the scope of the invention as set forth in the claims.

Fig. 1, is a perspective of the utensil folded into condition to be used as a carrying case.

Fig. 2, is a perspective showing the outfit

as unfolded and set up as a table, and 55 benches serviceable thereat and showing the lunch-box included in the outfit.

Fig. 3, is a perspective of the unfolded case-forming sections and is a view looking into the interior of the upturned sections, 60 one of which is partly broken away to show the folded legs.

Fig. 4, is a transverse sectional view across the unfolded case sections showing means for locking the same in open position. 65

Fig. 5, is a sectional view of a fragment of one of the case sections showing a step in the unfolding of one of the legs and showing its slidable carrier.

Fig. 6, is a view similar to Fig. 5, showing the carrier and its leg in locked position. 70

Fig. 7, is a sectional view transversely across one of the legs and through the frame of a case section on line 7—7 of Fig. 6, and illustrating in detail a form of lock. 75

Fig. 8, is an end view of the extended table top.

Fig. 9, is a perspective of the leg screw socket.

Figure 10 is a sectional view of a fragment of one of the case sections showing the leg 11 extended and in locked position. 80

The present invention consists of a portable camp table and dining outfit and includes a sectional box or case of such dimensions that it may be carried in hand and within which may be closely packed elements of the outfit such as benches or seats and a lunch or other box; legs being permanently connected to the respective sections and 85 which are capable of being arranged in a position to support the sections of the casing to form a table.

An embodiment of the invention is shown in which a casing consists of two substantially similar sections 2 and 2^a, of desired dimensions and material, these sections having contiguous frame portions 3, hingedly connected as at 4, so that the sections can be closed to meet at the edges 5, of the frames 100 of the sections and be suitably locked or latched as by fastening device 6. The case may have one of its sections provided with a carrying handle 7.

Preferably the bottom or side walls 8 and 9, of the sections are of such area as to form, when they are brought into a common plane when the sections are unfolded about their

22
hinges 4, a table top as shown in Fig. 2. To support the table thus provided each of the sections 2 and 2', has secured to its corners remote from the axes of the hinges suitable legs. Preferably the legs are rigid posts 10 and 11, the latter being connected by a plain gate hinge 12, to the inner surface of the panel 8, and preferably close to the side wall 5; the leg 11 being turnable to an open position about the axis of the hinge 12, so as to stand upright in the corner formed by the case frame and in which position it may be locked as by means of a thumb-screw 13, passing diagonally through an aperture provided in the leg and engaging in a threaded socket 14, mounted in the angle of the frame as in Fig. 7. Each of the legs of the device is adapted to be locked with such a fastening screw and when in its erected position, each leg is bound against the inner faces of the frame of the casing section and held rigidly.

In order to avoid interference between adjacent legs 10 and 11, of one section of the case and since these legs are each of a length nearly equal to the length of its section within the frame it is desirable to mount one of the legs, so that it can be relatively shifted to provide for the convenient folding and unfolding of the other leg into proper or desired position. To that end, each leg 10, of the pairs of legs is mounted on a pivot pin 10^a, extending inwardly perpendicularly from a sliding carrier in the form of a piece of strip iron 15, that is longitudinally slotted at 16, and slidably retained in place by a screw or retaining means 17, passing through the slot. The carrying strip 15, may be mortised into a recess 18, in the inner surface of the member 5, of the case frame so that it has guided movement thereon toward and from the contiguous transverse end wall of the frame. Thus the leg 10, is adapted to be pivoted on its pin 10^a, and this is shiftable as indicated in Figs. 5 and 6, so as to enable the unfolding and folding of the swinging leg 11, that is connected to a respective hinge 12. In setting up the table the folded legs 10 and 11, may be arranged in proper position by first swinging out from under the leg 10, the free end of the leg 11, after which the leg 10, can be swung to perpendicular position with its inner end moving down toward the side or panel 8, when it may be shifted with its sliding carrier 15, into abutment with the end wall of the frame section and locked by an inserted thumb-screw 13, Fig. 6. It will be seen that the innermost leg 11, must be cleared from below the swinging end of leg 10, before the latter can be set up.

After the case sections have been opened to the positions shown in Figs. 3 and 4, the sections are locked against hinge movement by passing bolt or other fastening means 20,

through apertures 21, provided therefor in 65 the hinged side members 3, of the frames.

To complete the utensil for dining purposes a bench or benches is or are included in the outfit as shown and may comprise a seat board 26, having supporting legs 27, at 70 the ends movably attached to the board 26, so that the collapsed benches can be compactly arranged in one section of the case while in the other section there may be arranged a lunch box 23.

75
This lunch box is shown as adapted to be elevated above and supported by the case structure so as to be conveniently accessible and not in the way. The box may be attached to the table top to be held steady and elevated at the same time by suitable means. Such means may comprise a set of legs 24, foldably connected to the ends of the box 23, and adapted to be slipped into sockets 25, provided in or on the case sections.

80
The table top may be provided with leaves 8^a, that may be folded down upon the sides of the case sections or extended to increase the area of the table top.

90
The socket 14, is preferably formed in or on corner stays having flanges 14^a, adapted to be secured to the corners of the frame of the sections of the case, thus securing a strong and rigid construction.

95
What is claimed is:

1. A convertible structure comprising a two section carrying case, the sections of which are adapted to be aligned to form a table, a bar slidable in each section adjacent the corner thereof, a leg pivoted in each section adjacent the opposite corner thereof, a leg pivoted on each slide bar, and means for securing the legs when extended in their respective corners.

100
2. A convertible structure comprising a two section carrying case, the sections of which are adapted to be aligned to form a table, a bar slidable in each section adjacent the corner thereof, a leg pivoted in each section adjacent the opposite corner thereof, a leg pivoted on each slide bar, a socket disposed in each corner and a thumb screw adapted to pass thru each leg into a socket to secure the legs when extended.

105
3. A table structure having a frame whose corners are bound in a corner stay provided with a socket, legs hinged to the frame and adapted to be set up in the corners of the frame, and means for engaging the sockets to secure the legs in erected place.

110
4. In a table construction having knock-down legs, a socket device having flanges to cover the corners of the top frame of the table, and means insertable in and for connecting a leg to the socket.

115
In testimony whereof, I have hereunto set my hand.

GUSTAF SANDBERG.
